H. T. THOMAS

LOCK FOR ELECTRIC CIRCUITS

Filed Dec. 6, 1920

UNITED STATES PATENT OFFICE.

HORACE T. THOMAS, OF LANSING, MICHIGAN.

LOCK FOR ELECTRIC CIRCUITS.

Application filed December 6, 1920. Serial No. 428,664.

To all whom it may concern:

Be it known that I, HORACE T. THOMAS, citizen of the United States, residing at Lansing, county of Ingham, State of Michigan, 5 have invented a certain new and useful Improvement in Locks for Electric Circuits, and declare the following to be a full, clear, and exact description of the same, such as will enable others skilled in the art to which 10 it pertains to make and use the same, reference being had to the accompanying drawings, which form a part of this specification.

My invention relates to a lock for electric 15 circuits and a special object of my improvement is to provide an improved lock for interrupting the ignition circuit upon an automobile. I secure this object in the device illustrated in the accompanying drawings, which form a part of this specification.

Figure 1 is a face elevation of a panel 20 adapted to be secured to the instrument board of an automobile, having an apparatus embodying my invention attached thereto in which:

Figure 2 is a rear view of the central portion of said panel to a large scale.

Fig. 3 is a section substantially on the line III—III of Fig. 2.

Fig. 4 is a detailed section of the lower portion of Fig. 3, the parts being in a different relative position.

Fig. 5 is a detailed perspective view of the guide plate.

a is a panel which may have instruments *b* and *c* in it and an observation light *d*.

e is a cylindrical aperture formed through the panel *a* having its outer portion somewhat enlarged. *f* is a cylindrical casing of 40 a pin-lock the barrel of which fits and is adapted to reciprocate in the narrower portion of the aperture *e*, its head reciprocating in the larger portion of said aperture. *g* is a guide plate having the overturned lugs 45 *g*² at its upper end. Said plate is secured to the inner end of the barrel of the lock, the lugs *g*² engaging against abutments *g*³ on the panel *a* so as to prevent the rotation of the barrel of the lock but to permit 50 the same to reciprocate in an axial direction. *f*² is a cylindrical rod passing through a corresponding aperture through the barrel *f* eccentric thereto and in the construction shown nearer the lower portion of said 55 barrel. *f*⁴ is a disc, having a circular

periphery, secured eccentrically upon the inner end of the rod *g*.

h is a locking pin adapted to reciprocate vertically in an aperture in the casing *a*. *h*² is a compression spring acting upon the pin *h* to normally and yieldingly hold it in its lowest position.

j is a spring secured to the casing *a* at its upper end having its lower end free and resting against the inner surface of the disc *f*⁴. The spring *j* normally holds lock barrel *f* with its attached parts in its outer position as shown in Fig. 4.

k is a contact piece also secured to the casing *a*. The spring *j* is adapted to make contact with the piece *k* to complete the ignition circuit when the lock barrel is at its furthest outer position as shown in Fig. 4.

When the lock barrel *f* is forced inward it separates the spring *j* from the contact piece *k* as shown in Fig. 3 thus breaking the ignition circuit.

When the rod *g* is turned to one position the eccentric disc *f*⁴ is carried beyond the upper portion of the barrel *f* as shown in Fig. 3 and when said barrel is forced to its innermost position the pin *h* engages in front of the disc *f*⁴, as shown in said figure, thus holding the barrel in its inner position and the spring *j* in the position in which the circuit is broken. When the rod *g* is turned to 180 degrees from the position shown in Fig. 3, and as shown in Fig. 4, the upper portion of its periphery is brought upon a level with the upper portion of the periphery of the barrel *f*, thus the barrel and disc may be moved under the pin *h* and will be so moved by the force of the spring *j* until contact is made with the piece *k* and the ignition circuit is then completed.

If the parts are so proportioned that in the last described position of the disc *f*⁴ the upper part of its periphery is below the upper part of the periphery of the barrel *f* the pin *h* will engage against the inner end of said barrel or the plate *g* thereon to prevent the inward movement of said barrel until the disc *f*⁴ is turned to a position which shall lift the pin *h* above the upper part of the barrel *f*.

The usual notched-edge key may be inserted in the key hole *f*⁵ to adjust the pins of the lock and thus the rod *f*² may be turned by the key to the desired position. When the parts are adjusted to the position

as shown in Fig. 3 and the key removed the ignition circuit is broken and the barrel *f* is prevented by its pins from being turned thus the ignition cannot be operated by an unauthorized person.

The observation light *d* is the usual metal surrounding casing or shade with the small opening therein as indicated more distinctly in Fig. 3. This lamp is rotatable 10 about its axis and may be placed so that the rays of light emitted from the casing will be thrown entirely upon the region of the speedometer or the ammeter, as indicated respectively by the lines A—A and 15 B—B in Fig. 1 of the drawings, in which case the lock will be in the shadow and will not be easily observed. The panel *a* is secured to the instrument board by screws or bolts entering from the opposite side of the 20 dash or instrument board from that upon which the panel is placed so that the securing means shall be inaccessible from the panel side.

The outer end of the casing is on a level 25 with the surface of the instrument board when the lock is not engaged and is entirely within said aperture when engaged.

Claims:

1. In an apparatus of the kind described, 30 an electric circuit, an inaccessible apparatus for making and breaking said circuit, an accessible part adapted to reciprocate to operate said make and break apparatus, a spring actuated bolt pressing against the 35 surface of said reciprocating part and a rotatable means carried by said reciprocating part adapted to engage said bolt to prevent or permit its engagement of said reciprocating

part to permit or prevent the motion of the same.

2. In an apparatus of the kind described, an electric circuit, an inaccessible apparatus for making and breaking said circuit, an accessible part adapted to reciprocate to operate said make and break apparatus, a spring actuated bolt tending to press laterally against the surface of said reciprocating part, a rotatable part extending through said reciprocating part, an eccentric cam on the inner end of said rotating part so arranged as to engage said bolt to lock said reciprocating part in its disengaging position or to be turned to a position to permit the movement of said reciprocating part.

3. In an apparatus of the kind described, an electric circuit, an inaccessible apparatus for making and breaking said circuit, an accessible part adapted to reciprocate to operate said make and break apparatus, a spring actuated bolt tending to press laterally against the surface of said reciprocating part, a rotatable part extending through said reciprocating part, an eccentric cam on the inner end of said rotating part so arranged as to engage said bolt to lock said reciprocating part in its disengaging position or to be turned to a position to permit the movement of said reciprocating part or to be turned to a position to permit said bolt to engage said reciprocating part to prevent the motion thereof.

In testimony whereof I sign this specification.

HORACE T. THOMAS.
